DRILLING OR BORING TOOL.

1,169,582.

Specification of Letters Patent. Patented Jan. 25, 1916.

Application filed March 21, 1912. Serial No. 685,292.

To all whom it may concern:

Be it known that we, WILLIAM MAINE TREGLOWN and WILLIAM NOBLE, subjects of the King of Great Britain and Ireland, both 5 residing at 165 Queen Victoria street, London, E. C., England, engineers, have invented certain new and useful Improvements Relating to Drilling or Boring Tools, of which the following is a specification.

10 This invention relates to drilling or boring tools and especially to percussive hammer drills and the like, and it has for its object to provide simple means to effect the regulation of the blow and stroke of the 15 machine and the periodic removal of the loose chips or debris from the drill or bore hole, so as to give a clear working face of rock, to increase the drilling capacity or to effect the release of the drilling tool when 20 this may have become bound in the hole.

According to the invention we provide on the exhaust, a valve or other device by means of which the piston of the drill may be prevented from operating or may be controlled 25 in such manner as to perform its strokes in the cylinder but without striking blows, to effect rotation, and by which the compressed air or other motive fluid may be caused to pass through the ports and through the hollow drill tool, so that any accumulation of 30 chips or debris in the bore or drill hole is expelled under the relatively high pressure and volume of air passing through, by which the binding of the drill tool in the drill or bore hole is avoided or overcome.

The invention is illustrated in the accompanying drawings as applied to a hammer drill of standard type.

Figure 1 is an elevation of the drill taken 40 at right angles to Fig. 2 showing the position of the valve by which the exhaust is throttled. Fig. 2 is an elevation in section of the drill, taken on a plane intersecting the valve box, the air passages in the cylinder 45 being shown displaced from their actual positions around the periphery of the cylinder to facilitate the description of the operation.

In carrying the invention into effect in its 50 application to a percussive drill of the construction illustrated in the drawings there is mounted upon the exhaust outlet a^2 of the valve casing a a plug valve b by which the

passage of the exhaust air may be throttled to any desired degree so that the force of the 55 blow given by the piston to the drill may be regulated to a fine degree or so that the piston merely reciprocates for the purpose of effecting the rotation of the drill or is prevented from operating while the compressed 60 air is caused to pass through the inlet ports of the drill and through the hollow drill tool for the expulsion of any accumulation of debris in the bore or drill hole.

In the operation of the drill illustrated 65 in the drawing, when the valve c is in its lowermost position and the piston f is in its uppermost position the lower inlet passage d^1 to the valve chamber communicates with the corresponding valve exhaust passage g through the passage d^2 and the annular space f^1 formed by the reduced middle portion of the piston, while the valve exhaust passage h is closed by the lower portion 70 of the piston and the valve c is therefore under the pressure of the compressed air or other motive fluid entering by the upper inlet passage e^1 . The valve is thus retained in its lowermost position and the air or other motive fluid enters the piston 75 cylinder by the upper inlet passage i .

Part of the compressed air acting upon piston f is free to pass between the teeth of the piston rifle nut f^2 and the grooves of the rifle bar j and down the bore f^3 of the piston 85 to the hollow drill tool k and thus to the drill hole. Similarly air can pass from the annular cylinder space below the lower portion of the piston between the rotation sleeve nut l and the central prolongation of the 90 piston. By means of the ratchet device m secured to the rifle bar j the piston is prevented from rotating and thus the drill k is rotated.

As the piston f passes down to give the 95 blow upon the drill k , the air in the lower annular cylinder space is free to exhaust through the lower inlet passage n and in the travel of the reduced middle portion of the piston the upper valve inlet passage e^1 100 is put into communication with the valve exhaust passage h through the passage e^2 and the annular space f^1 while the lower valve exhaust passage g is closed and the valve thus becomes open to the pressure of the air 105 entering the valve inlet passage d^1 . The

valve, therefore, rises and air is admitted to the cylinder by the lower inlet passage *n* while the upper inlet passage *i* is thrown open to the exhaust. The piston then rises 5 and partially rotates the ratchet device *m* to a new position.

The air is admitted to the valve box by the inlet *a*¹ while the exhausts both from the cylinder and the valve box pass out by 10 the exhaust outlet *a*² to which the valve *b* is applied.

It will be evident that during the operation of the drill a small amount of air will pass through the passage *f*³ from the back 15 of the cylinder during the forward stroke of the piston to the hollow drill steel, likewise, a certain amount will pass from the forward end of the cylinder around the central prolongation of the piston to the drill 20 steel during the backward stroke of the piston. This, however, is not sufficient to keep the hole clean at all times. When it is desired to thoroughly clear out the hole the valve *b* is closed, or almost closed, with the 25 result that the only exit from the cylinder is through the drill steel, whether by way of the passage *f*³, or around the central prolongation of the piston. It will be evident, therefore, that no matter what position the 30 piston happens to be in when the exhaust valve is closed, the air from the cylinder will pass to the drill steel and blow out the rock cuttings from the hole.

Instead of thus controlling the exhaust 35 we may cause the same effect by permitting the compressed air or other motive fluid to travel direct to the drilling tool; and we may, for example, provide a common valve for the supply of the motive fluid which in 40 one position may admit the motive fluid for the operation of the tool, while in another position it may completely close the supply of the motive fluid for the operation of the tool, and in yet another position it may admit 45 the motive fluid for the removal of the chips or debris from the drilling or boring hole for the purpose described. It will however be understood that a separate valve may also be used for the removal of the 50 chips or debris. By such means it will be understood that the drill hole is readily cleared from time to time to prevent the accumulation of chips or debris without the necessity of the removal of the drill or its 55 separation from the drilling or boring tool.

The invention is not limited to the particular form of controlling valve that may be employed, but we prefer to provide a valve which is provided and disposed so as 60 to be easily operable by the driller.

It will be understood also that the invention is not limited to the particular application hereinbefore described, but is applicable to all kinds of pneumatic or like tools 65 for the regulation of the operation and in

the case of the tools provided with several exhaust outlets each of these may be provided with a separate throttle valve.

What we claim as our invention and desire to secure by Letters Patent is:—

1. In a pneumatic percussive drill, a cylinder, a piston, a hollow drill steel actuated by said piston, passages for conveying fluid from both ends of said cylinder to the bore of said steel, and means for throttling the 70 exhaust of the drill.

2. In a pneumatic percussive drill, a cylinder, a piston, a hollow drill steel actuated by said piston, a passage through said piston to convey fluid to said drill steel from the 80 rear end of said cylinder, means to convey fluid from the front end of said cylinder to said drill steel, and means for throttling the exhaust from said cylinder.

3. The combination in a pneumatic tool of 85 means for the passage of live fluid from the rear of the working piston directly to the bore of a hollow drill or cutter carried by the tool for the purpose of removing debris from the working face and means for throttling the exhaust from the tool for the control of the operation of the tool and of the flow of live fluid for the removal of the debris from the working face, substantially 90 as described.

4. A pneumatic tool comprising a cylinder having ports for the admission and exhaust of fluid, a piston within said cylinder, a hollow drill or cutter carried by the cylinder, means for the direct passage of live 100 fluid from the rear of the piston to the bore of the hollow drill or cutter, means for the control of the admission and exhaust of fluid to and from the fore and rear ends of the piston and means for throttling the 105 exhaust from the tool substantially as described.

5. A pneumatic tool comprising a cylinder having ports for the admission and exhaust of fluid, a piston within said cylinder having a longitudinal passage or small cross-section, a hollow drill or cutter carried by the cylinder, means for the control of the admission and exhaust of fluid to and from the fore and rear ends of the piston for the operation 110 of the piston, and means for throttling the exhaust from the tool, substantially as described.

6. A pneumatic tool comprising a cylinder, a drill or cutter holder mounted upon the cylinder, a piston within the cylinder having a central prolongation extending into the drill or cutter holder, a longitudinal passage of small cross-section through said piston and prolongation, a hollow drill or cutter carried by the drill or cutter holder, means for the control of the admission and exhaust of fluid to and from the cylinder at each end of the piston for the operation of the piston, and means for throttling the 115 120 125 130 135

haust from the tool, substantially as described.

7. A pneumatic tool comprising a cylinder, a drill or cutter holder mounted upon the cylinder, a piston within the cylinder having a central prolongation extending into the drill or cutter holder, a longitudinal passage of small cross-section through said piston and prolongation, a hollow drill or cutter carried by the drill or cutter holder, a valve box connected with the cylinder by admission and exhaust ports, a valve in the valve box controlling the passage of the fluid to and from the cylinder and means for throttling the exhaust from the tool, substantially as described.

8. A pneumatic tool comprising a cylinder, a rotatable drill or cutter holder mounted upon the cylinder, a piston within the cylinder having a prolongation extending into the drill or cutter holder and engaging it by

surface grooves inclined to the axis, a rotatable ratchet device at the head of the cylinder with an axial stem having slideable connection with the piston, a longitudinal passage of small cross-section through said piston and prolongation, a hollow drill or cutter carried by the drill or cutter holder, a valve box connected with the cylinder by admission and exhaust ports, a valve in the valve box controlling the passage of the fluid to and from the cylinder and means for throttling the exhaust from the tool substantially as described.

In testimony whereof we have hereunto signed our names to this specification in the presence of two subscribing witnesses.

WILLIAM MAINE TREGLOWN.
WILLIAM NOBLE.

DISCLAIMER.

1,169,582.—*William Maine Treglown and William Noble, London, England.*

DRILLING OR BORING TOOL. Patent dated January 25, 1916. Disclaimer filed June 26, 1917, by the assignee, *Ingersoll-Rand Company*.

Enters this disclaimer—

“To that part of the claims in said specification which is in the following words, to wit:

“1. In a pneumatic percussive drill, a cylinder, a piston, a hollow drill steel actuated by said piston, passages for conveying fluid from both ends of said cylinder to the bore of said steel, and means for throttling the exhaust of the drill.”

[*Official Gazette July 17, 1917.*]

In Letters Patent No. 1,169,582.

It is hereby certified that in Letters Patent No. 1,169,582, granted January 25, 1916, upon the application of William Maine Treglown and William Noble, of London, England, for an improvement in "Drilling or Boring Tools," an error appears in the printed specification requiring correction as follows: Page 2, line 111, claim 5, for the word "or" read of; and that the said Letters Patent should be read with this correction therein that the same may conform to the record of the case in the Patent Office.

Signed and sealed this 31st day of July, A. D., 1917.
